DISPLAY STAND FOR GREETING CARDS AND THE LIKE

Joseph Oster, Cleveland Heights, Ohio, assignor to American Greetings Corporation, Cleveland, Ohio, a corporation of Ohio

Application December 9, 1957, Serial No. 48,837

Term of patent 14 years

(Cl. D80—10)

Fig. 1

Fig. 1 is a front perspective view of a display stand for greeting cards and the like showing my new design;

Fig. 2 is a rear perspective view thereof; and

Fig. 3 is a fragmentary cross-sectional view showing two of the shelves on an enlarged scale.

It is understood that the fragmentarily disclosed expanded metal extends throughout the area of the shelves.

I claim:

The ornamental design for a display stand for greeting cards and the like, as shown and described.
